H. F. JOSEPH

PISTON FOR INTERNAL COMBUSTION ENGINES

Filed Dec. 15, 1921

Harry F. Joseph, INVENTOR.

BY

G. G. Bush

ATTORNEY.

UNITED STATES PATENT OFFICE.

HARRY F. JOSEPH, OF DAVENPORT, IOWA, ASSIGNOR OF ONE-HALF TO A. G. BUSH, OF DAVENPORT, IOWA.

PISTON FOR INTERNAL-COMBUSTION ENGINES.

Application filed December 15, 1921. Serial No. 522,648.

To all whom it may concern:

Be it known that I, HARRY F. JOSEPH, a citizen of the United States, residing at Davenport, in the county of Scott and State of Iowa, have invented certain new and useful Improvements in Pistons for Internal-Combustion Engines, of which the following is a specification.

My invention relates to improvements in 10 pistons for internal combustion engines; and the objects of my invention are, first, to obviate the necessity of piston rings; second, to construct a piston which will automatically adjust itself to a cylinder; third, to 15 provide for automatically expanding the piston to take up any wear in the cylinders; fourth, to provide means for utilizing bronze, aluminum or other metal for the wearing faces of a piston; fifth, to provide 20 for the use of an aluminum body for pistons faced with a harder metal to avoid wear; sixth, to provide means to prevent the scoring of cylinders by the wrist pins; seventh, to provide a durable, light weight 25 piston; eighth, to provide means which will allow the surface plates of a piston to expand without allowing the gases or compressed air to blow by while the piston is in motion; ninth, to provide a piston which 30 will readily adapt itself to manufacture in quantities and which can be easily assembled and adjusted; tenth, to provide spring-held means for expanding the outer surface of a piston combined with means for locking the 35 spring-held means in position longitudinally upon the piston; eleventh, to provide means for replacing the wearing surface of a piston without replacing the entire body thereof.

40 I attain these objects by the mechanism illustrated in the accompanying drawings, in which—

Figure 1 is a vertical elevation of a piston, but showing the right half in section on the middle line; Fig. 2 is a detail of one of the removable segments; Fig. 3 is a detail showing the adjusting ring; Fig. 4 is an end view of one of the removable segments; Fig. 5 is a detail of the adjusting ring; Fig. 6 is a detail 50 of the lock nut; Figures 7 and 8 are details of the lock spring; Fig. 9 is a detail of the tension spring and Fig. 10 is a detail of the lock nut.

Similar numerals refer to similar parts throughout the several views.

55 My piston consists of a body, 1, comprising a head and side walls with a hub 2, formed integral therewith to receive the wrist pin which secures the piston to the connecting rod.

60 The upper portion of the piston forms a head, the lower edge of which is bevelled as shown at 6 to correspond with the bevel upon the upper end of removable segments, 3. There are preferably four removable segments, 3, but the number may be increased or diminished to meet the requirements of any particular case. The upper and lower ends of the removable segments are bevelled at a suitable angle. For most purposes, I 65 prefer an angle of approximately 30° from the vertical, but it is obvious that this angle may be increased or diminished as the requirements of each particular case demand.

65 The segments 3, have their inner surfaces curved as shown in Figure 4, to correspond with the outer surface of the body 1, of the piston, but an open space 7, is preferably left between the middle portions of the segments and the piston to lighten the casting 80 and allow for expansion. The open space 7, is preferably surrounded by a ribbed portion which extends inwardly from the segments and normally makes a close contact with the body of the piston, but obviously 85 will be thrown out of immediate contact with the body of the piston when the segments are forced outwardly by the adjusting ring 9.

90 The upper and lower ends of the segments 3, are bevelled and are also provided with overlapping tongues 5, which correspond and fit into seats 4, formed in the adjacent side of the adjoining segment. Each segment is provided with two tongues 5, with 95 two seats 4, so that the four segments interlock and form a complete and tight circumference for the piston when in position.

90 Shallow oil grooves 8, are formed in the segments extending all the way around the 100 piston.

The segments are held in place against the piston by the cylinder wall and by an adjusting ring 9, which surrounds the body of the piston 1, and is locked in position by a 105 lock nut 19, which is threaded on the inside

and secured upon corresponding threads formed at the lower end of the piston. A spring 17, is riveted to the body of the piston by rivets 11, and its lower end is adapted to enter recesses 16, cut in the lower edge of the lock nut and in that manner to secure the lock nut against turning.

A compression spring preferably of wire, is seated in the groove 12, between the adjusting ring 9, and the lock nut 19.

This spring surrounds the body of the piston and undulates vertically as shown in Figure 9 so as to bear downwardly upon the lock nut 19, and against the adjusting ring 9.

15 While the spring 18, is preferably made of wire, it may be made of any suitable form of spring material and may be varied in size and proportions to fit the requirements of each particular case.

20 For clearness of illustration, the section lines are omitted in Figure 1 from the adjusting ring and lock nut, but the adjusting ring is in the form shown by the section 20, in Figure 3 and Figure 10 shows 25 the form of the lock nut.

The adjusting ring 9, is slit as shown at 10 so as to allow something for contraction and expansion.

In the manufacture of my piston, I prefer to form the body of die-cast aluminum and die-cast the segments either of aluminum or bronze, but it is obvious that other materials may be used as desired and I do not limit myself to these particular forms.

30 The pistons and segments may also be cast in the ordinary way and machined if desired.

In assembling my device, the segments are interlocked and placed upon the piston body. The adjusting ring 9, is then placed upon the lower end of the piston, and the spring 18, placed adjacent thereto and inserted in the groove 12. The lock nut 19, is then screwed upon the lower end of the

45 piston, locking the spring in the groove 12, and the lock nut is turned up tight enough to cause the desired pressure upon the spring 18. The lock nut is then secured in position by allowing the lower end of the spring

50 17, to catch in one of the recesses 16, and secure it against turning. As the interior walls of the cylinder are worn by the pressure of the piston, the pressure of the spring upon the adjusting ring 9, will tend to drive

55 it toward the top of the piston, producing a wedging action upon the segments 3, and forcing them outward radially from the body of the piston, thus holding them in close contact with the interior wall of the cylinder. The overlapping tongues 5, will prevent the escape of gases or compressed air past the segments.

In case the segments are worn by use, they may be replaced without replacing the 60 body of the piston.

It is obvious that the form, size and proportions of the various parts may be altered to fit the requirements of different cases without departing from the spirit of my invention.

70 It is also obvious that the bevel at the top of the piston may be formed integral with the body of the piston as shown in the drawings or a separate bevel ring may be used similar to the slip or adjusting ring shown in the drawings at the lower end of the piston. In practice, I prefer to have the spring mounted at the lower end of the piston as it will keep cooler in that position than if the slip or adjusting ring 75 and the spring are mounted at the upper end of the piston.

I claim:

1. In a piston, the combination with a body having a head bevelled upon its lower edge, of a plurality of segmental plates bevelled at their upper ends to correspond to the bevel of the head, and with bevels formed at the lower ends of the plates, and means for exerting pressure outwardly and 80 upwardly against the plates.

2. In a piston, the combination with a body having a head bevelled upon its lower edge, of a plurality of segmental plates bevelled at their upper ends to correspond to the bevel of the head, and with bevels formed at the lower ends of the plates, and an adjusting ring slidingly mounted upon 85 the lower end of the piston.

3. In a piston, the combination with a body having a head bevelled upon its lower edge, of a plurality of segmental plates bevelled at their upper ends to correspond to the bevel of the head, and with bevels formed at the lower ends of the plates, and an adjusting ring slidingly mounted upon the lower end of the piston having its upper 90 surface bevelled to correspond with the bevel of the lower ends of the segmental plates.

4. In a piston, the combination with a body having a head bevelled upon its lower edge, of a plurality of segmental plates bevelled at their upper ends to correspond to the bevel of the head, and with bevels formed at the lower ends of the plates, an adjusting ring slidingly mounted upon the lower end of the piston having its upper surface bevelled to correspond with the bevel of the lower ends of the segmental plates, and means for securing the adjusting ring 100 snugly against the bevelled lower ends of the segmental plates.

5. In a piston, the combination with a body having a head bevelled upon its lower edge, of a plurality of segmental plates bevelled at their upper ends to correspond to the bevel of the head, and with bevels formed at the lower ends of the plates, an adjusting ring slidingly mounted upon the lower end of the piston having its upper 105 110 115 120 125 130 135

face bevelled to correspond with the bevel of the lower ends of the segmental plates, and spring operated means for securing the adjusting ring snugly against the bevelled lower ends of the segmental plates.

6. In a piston, the combination with a body having a head bevelled upon its lower edge, of a plurality of segmental plates bevelled at their upper ends to correspond to the bevel of the head, and with bevels formed at the lower ends of the plates, an adjusting ring slidably mounted upon the lower end of the piston having its upper surface bevelled to correspond with the bevel of the lower ends of the segmental plates, a lock nut threaded upon the lower end of the piston body, and an adjusting ring slidably mounted on the piston above the lock nut.

10. 7. In a piston, the combination with a body having a head bevelled upon its lower edge, of a plurality of segmental plates bevelled at their upper ends to correspond to the bevel of the head, and with bevels formed at the lower ends of the plates, an adjusting ring slidably mounted upon the lower end of the piston having its upper surface bevelled to correspond with the bevel of the lower ends of the segmental plates, a lock nut threaded upon the lower end of the piston body, an adjusting ring slidably mounted on the piston above the lock nut, and a spring mounted between the lock nut and the adjusting ring.

35. 8. In a piston, the combination with a body having a head bevelled upon its lower edge, of a plurality of segmental plates bevelled at their upper ends to correspond to the bevel of the head, and with bevels formed at the lower ends of the plates, an adjusting ring slidably mounted upon the lower end of the piston having its upper surface bevelled to correspond with the bevel of the lower ends of the segmental plates, a lock nut threaded upon the lower end of the piston body, an adjusting ring slidably mounted on the piston above the lock nut, and an undulating circular spring seated between the lock nut and the adjusting ring.

45. 9. In a piston, the combination with a body having a head bevelled upon its lower edge, of a plurality of segmental plates bevelled at their upper ends to correspond to

the bevel of the head, and with bevels formed at the lower ends of the plates, an adjusting ring slidably mounted upon the lower end of the piston having its upper surface bevelled to correspond with the bevel of the lower ends of the segmental plates, a lock nut threaded upon the lower end of the piston body, an adjusting ring slidably mounted on the piston above the lock nut, a spring seat formed in the lower and inner edge of the adjusting ring, a corresponding spring seat formed in the lock nut and a spring seated in the spring seats.

10. In a piston, the combination with a body having a head bevelled upon its lower edge, of a plurality of segmental plates bevelled at their upper ends to correspond to the bevel of the head, and with bevels formed at the lower ends of the plates, an adjusting ring slidably mounted upon the lower end of the piston having its upper surface bevelled to correspond with the bevel of the lower ends of the segmental plates, a lock nut threaded upon the lower end of the piston body, an adjusting ring slidably mounted on the piston above the lock nut, a spring seat formed in the lower and inner edge of the adjusting ring, a corresponding spring seat formed in the lock nut and an undulating circular spring seated in the spring seats.

11. In a piston, the combination with a suitable body having a bevelled head formed at the top thereof, of a bevelled adjusting ring slidably mounted upon the body near the lower end thereof, a lock nut threaded upon the lower end of the body adjacent the adjusting ring, and segmental plates mounted upon the body between the bevelled head and the bevelled adjusting ring.

12. In a piston, the combination with a suitable body having a bevelled head formed at the top thereof, of a bevelled adjusting ring slidably mounted upon the body near the lower end thereof, a lock nut threaded upon the lower end of the body adjacent the adjusting ring and interlocking segmental plates mounted upon the body between the bevelled head and the bevelled adjusting ring.

In testimony whereof he affixes his signature.

HARRY F. JOSEPH.
